UNITED STATES PATENT OFFICE.

JOSEPH MAZER, OF McALESTER, OKLAHOMA.

WINDING-INDICATOR.

1,108,510.

Specification of Letters Patent.

Patented Aug. 25, 1914.

Application filed November 18, 1911. Serial No. 661,132.

To all whom it may concern:

Be it known that I, JOSEPH MAZER, a citizen of the United States, and resident of McAlester, in the county of Pittsburg and State of Oklahoma, have invented a new and useful Improvement in Winding-Indicators; and I do hereby declare the following to be a full, clear, and exact description thereof.

My invention relates to a winding indicator to be used in connection with watches, clocks, phonographs or other devices to which it may be found applicable, whereby it is possible by a dial located in view and an indicator hand to tell not only when the main-spring is fully wound or when it is run down, but also the extent to which it is wound at any particular moment and the time when it will require rewinding.

The object of my invention is to provide a simple form of mechanism in which there are a small number of parts and the parts so arranged as to be confined within a narrow space, all as fully hereinafter set forth.

Referring to the drawings, Figure 1 is a face view of a watch with my invention applied thereto; Fig. 2 is an enlarged plan view of a portion of the watch plate with the dial plate removed; Fig. 3 is a section on the line 3—3 Fig. 2; Fig. 4 is a section on the line 4—4 Fig. 2; Fig. 5 is a section on the line 5—5 Fig. 2; and Figs. 6 and 7 are views of a modified form of my invention.

In the drawings I have illustrated my invention as applied to a watch A of any suitable construction with an ordinary movement which it has not been deemed necessary to illustrate.

The letter o designates the main-spring barrel within which is the main-spring o'. The ratchet wheel i is attached to the barrel-arbor o³ and said ratchet wheel meshes with the winding wheel H. Meshing with the winding wheel H is the pinion k mounted on a pin l at the lower end of which is the gear-wheel m connecting directly with the gear-wheel f. This gear-wheel f has the annular projection f' which engages a shoulder f² in the sun gear g. Connected to or formed integral with the plate k' is the stud d. The sun gear g is loosely mounted on the stud d.

The gear-wheel f is provided with the crown-teeth f³. The teeth f³ mesh with the planet-gear e carried by the stud g' on the disk g. The disk g is mounted loosely on the stud d which is connected to lower plate k'. The gear-wheel e meshes with the pinion

portion h' of the gear-wheel h. The gear-wheel h has the flange h² to encircle the flange f' of the gear-wheel f. This gear-wheel h is also mounted loosely on the stud d. The cap-screw d' is threaded into the stud d and acts to hold down the double gear h and planetary disk g. The gear-wheel h is also provided with the spur teeth h³ which mesh with the pinion n on the center-wheel staff l', which in turn meshes with the spring-barrel. The sun gear g has the pinion p formed central with said disk which meshes with an intermediate gear r. The gear r meshes with the indicator hand gear-wheel s.

When the watch is unwinding the barrel rotates, the ratchet being held stationary, and by the rotation of the barrel the center pinion n being in engagement with the barrel and meshing with the teeth h³ of the double gear-wheel h. The pinion h' of gear-wheel h meshes with the planetary-gear e which meshes with the vertical teeth f³ of the crown-wheel f. As the crown-wheel f is held from rotation by its engagement indirectly with the ratchet-wheel, the gear-wheel e being loosely fastened to the sun gear g and traveling in its orbit carries the sun gear g, which having the pinion p meshing with intermediate gear r rotates the indicator hand gear s. When the watch is being wound, the pinion x engaging winding wheel H rotates the ratchet-wheel and winds up the spring. At the same time the winding wheel H rotates pinion k mounted on arbor l carrying at its lower end pinion m which meshes with the spur teeth of wheel f. This imparts rotation to planetary wheel e which being loosely mounted on the sun gear g rotates said disk together with the wheel f which in turn rotates intermediate gear r which rotates indicator hand-wheel s in opposite direction returning same to zero.

In Figs. 6 and 7 I have illustrated modified form of my invention in which the entire mechanism is under the spring-barrel. The spring barrel 5 is provided with the pinion 6 rigidly attached thereto which meshes with the planetary-wheel 7 loosely mounted on the sun gear disk 8. The sun gear 8 carries with it the pinion 10 which meshes with the intermediate gear 11 which meshes with indicator hand-wheel 12. The gear-wheel 9 is provided with spur teeth 9^a which engage the planetary wheel 7. The gear-wheel 9 has also the teeth 9^b which

mesh with an intermediate pinion 13, said pinion meshing with a pinion 14 on the staff 15 which carries a gear-wheel 16 at its upper end and engages the ratchet wheel 17.

5. What I claim is:

1. In a watch or the like, the combination of the main-spring barrel, winding mechanism including a ratchet-wheel, an indicator hand, a stud on the watch-plate, gear-mechanism mounted on said stud, connections between said mechanism and indicator hand, connections between said gear-mechanism and said ratchet wheel in reversing, connections between said gear-mechanism 15 and said spring-barrel in unwinding, and a cap engaging said stud to hold said mechanism in place.

2. In a watch or the like, the combination of the main-spring barrel, winding mechanism including a ratchet-wheel, a combined spur and crown tooth gear-wheel, connections between said ratchet-wheel and the spur teeth of said gear, an indicator-hand, and connections between the crown teeth of said gear and said indicator-hand for operating the same.

3. In a watch or the like, the combination of the main-spring barrel, winding mechanism including a ratchet-wheel, a combined spur and crown tooth gear-wheel engaging with the upper plate of the watch and supported therein, connections between the spur teeth of said gear-wheel and the ratchet-wheel, an indicator hand, and connections between the crown teeth of said gear and said indicator-hand for operating the same.

4. In a watch or the like, the combination of the main-spring barrel, winding mechanism including a ratchet-wheel, a combined spur and crown tooth gear-wheel, connections between said ratchet-wheel and the spur teeth of said crown gear, a planet-gear engaging the crown teeth of said gear, an indicator-hand, and connections between said planet-gear and said indicator hand for operating the same.

In testimony whereof, I the said JOSEPH MAZER have hereunto set my hand.

JOSEPH MAZER.
